ASPIRATOR ASSEMBLY

Lyman F. Whitney, Cambridge, Mass., assignor,
by mesne assignments, to Stator Corporation, a
corporation of Rhode Island

Application May 25, 1938, Serial No. 209,874

5 Claims. (Cl. 230—95)

This invention relates to an improved aspirator assembly and more particularly to an improved nozzle-mounting arrangement for such an assembly. In some respects the present invention provides a further development of or an improvement upon the nozzle-mounting arrangements disclosed in my United States Patent No. 1,710,910, dated April 30, 1929, and Wescott Patent No. 1,694,087, dated December 4, 1928. 5 The arrangement disclosed herein may also be employed to particular advantage with aspirator assemblies of the type disclosed in my copending application Serial No. 177,749, filed December 2, 1937. 10 As disclosed in the above-identified Wescott patent, it is highly desirable to arrange an aspirator nozzle so that it may be accurately aligned with the aspirator funnel. Furthermore, as disclosed in both of the above-identified patents, it is desirable to arrange the nozzle so that 15 only a minimum heat flow may take place between the riser pipe supplying hot propellant vapor to the nozzle and the mixing chamber of the aspirator assembly. For this purpose, as disclosed in the above-identified patents, the nozzle itself may be made of thin metal of relatively low heat conductivity, and the dome of the mixing chamber through which the nozzle extends also 20 preferably may be made of similar material. 25 In accordance with this invention, a suitable rod may extend from the nozzle to a supporting bracket, the rod being so arranged that the nozzle may be properly held in alignment by the bracket. For this purpose I prefer to provide a bracket of U-shaped form extending from the 30 opposite sides of the mixing chamber to a region spaced from the dome of the same, the bight portion of the U-shaped bracket being disposed in this region and supporting one end of the rod. 35 The rod preferably is formed of metal of low heat conductivity, such as stainless steel or nichrome. 40

The bracket also may be formed of metal of low heat conductivity and may be provided with 45 openings of substantial size to impede heat flow therethrough, it being understood that the bracket provides relatively long paths for the flow of heat.

In the accompanying drawing: 50 Fig. 1 is a sectional view of an aspirator assembly having a nozzle-mounting arrangement in accordance with this invention;

Fig. 2 is an enlarged view of the mixing chamber and nozzle-mounting arrangement on a plane 55 at right angles to that of Fig. 1; and

Fig. 3 is an end elevation of the aspirator assembly showing the nozzle-mounting arrangement.

The accompanying drawing shows an aspirator assembly of the general character disclosed in my above-identified copending application. Such an assembly comprises a funnel 1 with a throat 2 and with a cooling jacket 3. If desired, the funnel may be provided with a plurality of fins 4 disposed within the cooling jacket. The assembly is also provided with a mixing chamber 5 which receives vapor from a supply duct 6. The mixing chamber 5 is provided with a dished end wall or dome 7, through which the nozzle 8 may extend. The dome 7 may be of thin 15 metal of low heat conductivity, such as nichrome or stainless steel, and may be capable of being distorted slightly to permit adjustment of the angular position of the nozzle 8.

The nozzle 8, as shown in Fig. 2, is arranged 20 to receive propellant vapor through a tube 9. The connection between the tube and the nozzle is provided with a short tubular extension 10 extending away from the nozzle. Bars 11 preferably are welded to the head 5 of the nozzle and extend outwardly from opposite sides thereof to afford supports for the opposite sides of a U-shaped bracket 12. This bracket may be provided by bending a suitable channel into a U-shaped form, as shown. This channel preferably 25 is provided with openings 13 of substantial diameter to impede the flow of heat from the head to the bight portion of the bracket; if desired the bracket may be made of metal of low heat conductivity, such as nichrome or stainless steel. 30

The intermediate part of the bight portion of the bracket 12 is provided with a central opening 16. A rod 17 formed of metal of low heat conductivity, such as nichrome or stainless steel, extends between the nozzle assembly and the 35 bight portion of the bracket. Preferably the rod 17 may be considered as being formed in two parts, namely, the rod proper 17^a and a button 17^b in which the end of the rod proper fits with a tight sliding fit. The button has a portion of reduced diameter extending through the opening 16, and a head portion adapted to engage the outer surface of the bight portion of bracket 12. It will be understood that both the button 17^b and the rod proper 17^a are preferably 40 formed of metal of low heat conductivity. The inner end of rod 17^a preferably is welded to a metal plug 19, which fits within and is welded to the short tubular extension 10 of the nozzle assembly. 45

50 55

When the parts are first assembled they may be arranged in the manner which has been described, it being noted that the opening 16 is somewhat larger than the corresponding portion 5 of the bushing 17^b which extends therethrough, so that the angular position of the rod 17 is then only approximately determined. Thereafter, the nozzle 8 may be brought into accurate alignment with the funnel 1 by means of a suitable 10 aligning bar, as more fully disclosed in the co-pending application of Russell A. Gulick, filed on even date herewith. After the nozzle is thus brought into accurate alignment with the funnel, the enlarged portion of the bushing 17^b is secured 15 to the bight portion of the bracket 12 by brazing 20.

It is evident that the present invention affords a simple and effective arrangement for holding an aspirator nozzle in accurate alignment with 20 an aspirator funnel, and that such an arrangement is particularly advantageous in avoiding unnecessary heat losses. The bracket 12 affords relatively long paths of low heat-conductivity extending away from the head of the aspirator assembly, while the rod 17 also affords a path of 25 low heat-conductivity and of relatively small cross section. The provision of the U-shaped bracket 12 affords symmetrical supporting means for the rod so that heat expansion does not tend to cause movement of the nozzle out of alignment with the funnel.

It should be understood that the present disclosure is for the purpose of illustration only 35 and that this invention includes all modifications and equivalents which fall within the scope of the appended claims.

I claim:

1. An aspirator assembly comprising a mixing 40 chamber, a funnel extending from the mixing chamber, a duct to supply fluid to the mixing chamber, said mixing chamber having an end wall, a nozzle secured to said wall in alignment with said funnel, a duct for supplying vapor to 45 said nozzle, a rod extending from said nozzle, a bracket extending from said mixing chamber and having a portion remote therefrom to which the rod is fixed, thereby to hold the nozzle in alignment with the funnel, said rod being formed of 50

metal of low heat conductivity to impede the flow of heat away from the nozzle.

2. An aspirator assembly according to claim 1, wherein the bracket is a U-shaped metal member connected to opposite sides of the mixing 5 chamber and having its bight portion connected to the rod.

3. An aspirator assembly comprising a mixing chamber, a funnel extending from the mixing chamber, a duct to supply fluid to the mixing 10 chamber, said mixing chamber having an end wall, a nozzle secured to said wall in alignment with said funnel, a duct for supplying vapor to said nozzle, a rod extending from said nozzle substantially in alignment with said funnel, a U- 15 shaped bracket connected to opposite sides of the mixing chamber and having its bight portion spaced from said chamber, said rod being secured to the bight portion of said bracket.

4. An aspirator assembly comprising a mixing 20 chamber, a funnel extending from the mixing chamber, a duct to supply fluid to the mixing chamber, said mixing chamber having an end wall, a nozzle secured to said wall in alignment with said funnel, a duct for supplying vapor to 25 said nozzle, a rod extending from said nozzle substantially in alignment with said funnel, a U-shaped bracket connected to opposite sides of the mixing chamber and having its bight portion spaced from said chamber, said rod being secured to the bight portion of said bracket, said bracket being formed of metal of low heat-conductivity to impede the flow of heat away from the nozzle.

5. An aspirator assembly comprising a mixing 35 chamber, a funnel extending from the mixing chamber, a duct to supply fluid to the mixing chamber, said mixing chamber having an end wall, a nozzle secured to said wall in alignment with said funnel, a duct for supplying vapor to 40 said nozzle, a rod extending from said nozzle substantially in alignment with said funnel, a U-shaped bracket connected to opposite sides of the mixing chamber and having its bight portion spaced from said chamber, said rod being secured 45 to the bight portion of said bracket, both said rod and said bracket being formed of metal of low heat conductivity to impede the flow of heat away from the nozzle.
